HEAT RECUPERATION

Application filed January 28, 1925. Serial No. 4,880.

The present invention relates to improvements in heat recuperation, and more particularly to a method of and apparatus for effecting rapid and efficient heat transfer from a body of heating gas to a body of gas to be heated through the medium of metal diaphragms.

Many industrial processes, particularly those involving heat treatment of materials at high temperatures, are concerned very directly with the problem of effecting the transmission of heat from one body of gas to another through the medium of refractory or metal walls. It is well known that this system offers a good deal of resistance to the passage of heat. As it is now fairly well established that the greatest factor in the resistance to the passage of heat from one body of gases to another through recuperator walls is not the resistance of the walls themselves, but is the resistance of the dead gas films which adhere very tenaciously to both sides thereof, very little apparent increase in heat transfer can be obtained by simply replacing refractory sections by sections of high temperature metal in the ordinary type of recuperator commonly employed for preheating gas or air.

In using the ordinary type of metal or refractory recuperator for preheating air or gas by heat exchange with sensible heat in a gaseous heating medium, as for instance heat in waste products of combustion leaving a heat treating operation, very low rates of heat transfer must usually be accepted because all the heat given up by the gas must first pass by convection to the outside of the recuperator diaphragm, then by conduction through the diaphragm, and thence by convection to the gas or air which is being heated. In general the conduction of the diaphragm, particularly when of metal construction, is very high as compared with the conduction of the films of dead gases which adhere to the surfaces of the diaphragm and produce what is called "skin effect."

The primary object of the present invention is to provide a method of and apparatus for effecting rapid and efficient transfer of

heat from one body of gases to another through the medium of metal walls.

In accordance with this object one feature of the invention contemplates improving the design and arrangement of the ordinary type 55 of metal sectioned recuperator to minimize the "skin effect" and to decrease the resistance normally offered to heat transfer.

Another object of the present invention is to provide improvements in methods and 60 apparatus for heat transfer by means of which the rate at which a current of air or other gas is normally preheated by indirect heat transfer with a heating gas through the medium of metal walls is materially increased. 65

It has been found that heat transferred by radiation is entirely independent of the "skin effect" of dead gas films adhering to recuperator walls and is only interfered with by 70 solid bodies, which absorb or reflect this heat.

Accordingly another feature of the invention contemplates materially increasing the effectiveness of the ordinary type of metal sectioned recuperator by employing relatively inexpensive heat absorbing and heat radiating bodies positioned in such a way as to enlarge the effective heating surface of the recuperator and to make advantageous use of the known independence to "skin effect" of 80 heat transfer by radiation for reducing the resistance effect of adhering gas films to the normal methods of heat transfer by convection and conduction. 85

Another object of the invention is to provide, in an apparatus for the indirect transfer of heat from a current of heating gas to a current of gas to be heated through the medium of metal walls, means for continuing the heating operation of the gaseous 90 medium taking up heat during intervals in which the flow of gas giving up heat is suspended.

With these and other objects and features in view the invention consists in the method 95 of and apparatus for effecting rapid and efficient heat transfer from hot to cold gases through the medium of metal walls, herein-after described and particularly defined in the claim. 100

The various features of the invention are illustrated in the accompanying drawings, in which:

Fig. 1 is an elevation in diametrical section 5 of an upright cylindrical recuperator equipped with upright metal conduits of circular section having refractory cores and surrounded by refractory checker brick, in accordance with the preferred form of the invention;

Fig. 2 is a horizontal sectional view of one of the tubular metal conduits and its refractory core, taken on the line 2—2 of Fig. 1;

Fig. 3 is a sectional plan view of a similar 15 type of tubular conduit, illustrating a modified form of refractory core;

Fig. 4 is a sectional plan view of a tubular metal conduit loosely filled with broken 20 lumps of refractory material;

Fig. 5 is a sectional plan view of one of the tubular conduits, illustrating the preferred arrangement of refractory checker brick around the outside of the conduit;

Fig. 6 is a sectional plan view of metal 25 conduits of rectangular section equipped with a modified form of refractory core and surrounded and separated by refractory partitions resembling in shape the refractory core;

Fig. 7 is a horizontal sectional view taken 30 on line 7—7 of Fig. 8 of one end of a modified form of rectangular recuperator having narrow upright metal conduits separated by and spaced from relatively bulky refractory partition walls, designed particularly for both regenerative and recuperative service;

Fig. 8 is a sectional elevation of the rectangular recuperator illustrated in Fig. 7 35 taken on the line 8—8 of Fig. 7;

Fig. 9 is a sectional plan enlargement of one end of one of the narrow metal conduits illustrated in Figs. 7 and 8, with its refractory core.

The method of effecting rapid and efficient heat transfer from a heating gas to a 40 gas to be heated through the medium of a metal wall or diaphragm which comprises the preferred form of the present invention is of particular advantage when applied to the continuous preheating of gas or air or steam or to two or more of these materials simultaneously or alternately by means of sensible heat recovered from products of combustion leaving a high temperature heat treating operation.

The plan of operation normally employed 45 in such preheating processes, whereby heat first passes from the hot products of combustion by convection to the outside of the metal diaphragm, thence by conduction through the diaphragm and thence by convection to the gas or air which is being heated, is varied and improved upon according to the present invention by placing a body of relatively inex-

pensive material having good heat radiating, heat resisting and heat absorbing properties on one or both sides of the metal diaphragm in the path of the hot or cold gases or both hot and cold gases and spaced from the surface of the diaphragm to absorb additional heat from the heating gas for transmission directly to the metal surface by radiation and to absorb heat radiated from the opposite surface of the diaphragm for transmission by convection from the enlarged heating surface thus exposed to the gas undergoing preheat. More specifically the present invention is based on the use of firebrick, carborundum or other refractory material having good heat radiating and heat absorbing properties and having a low cost per square foot of heating surface as compared to high temperature metal, for economically increasing the effective heating surface exposed to a current of 50 gas to be heated as it flows past one side of a metal recuperator diaphragm. This same form of construction is used for increasing the effective heat absorbing and heat transmitting surface exposed to the current of heating gas flowing past the opposite side of the metal diaphragm. Thus, according to the present method, the amount of heat normally transferred directly from the heating gas to the metal by convection, thence through the 55 metal by conduction and thence to the cold gas by convection, is supplemented by the indirect transfer of additional heat from the heating gas to the metal, by convection to the refractory and thence by radiation to the 60 metal, and by the transfer of additional heat from the metal to the gas to be heated indirectly by radiation to refractory and thence by convection to the cold gas.

The apparatus employed for carrying out 65 the preferred method comprises a housing 10 having walls 12 of heat insulating material built in the form of an upright cylinder (see Fig. 1), or of a prone hexahedron (see Figs. 7 and 8) or in almost any other shape desired, the exact form and design of the housing being optional so far as the present invention is concerned. This housing 10 has an air or gas distributing chamber 14 in its lower portion above a base 16, preferably of refractory material, and an inlet 18 opening into chamber 14 for the admission of the steam, air or gas to be preheated. In the upper part of the housing there is a chamber 20, or, in the modified form of apparatus illustrated in Fig. 8, horizontal flues 20a, for collecting the hot air or gas after the preheating operation, such chamber 20 and flues 20a communicating with an offtake 22.

The major portion of the interior of housing 10 is taken up by a heating chamber 24 which is separated from the distributing chamber 14 by a flue sheet or header 26 and is also separated from the collecting chamber 20 at the top of the recuperator by a similar 130

header 28. Extending between headers 26 and 28, or between header 26 and flues 20a (see Fig. 8), there are a plurality of metal conduits 30 having circular, rectangular, or other odd shaped cross sections (see Figs. 5, 6 and 7). Such conduits serve as externally heated preheating chambers for the air, steam or other gas during its passage between chamber 14 and chamber 20 or flues 20a. Hot products of combustion or other hot gaseous heating media enter the top of heating chamber 24 from an external source of heat (not shown) through an inlet 32, and after passing downwardly through the heating chamber and in direct heat transferring relationship with the outer surface of conduits 30, and thereby becoming substantially cooled by indirect heat transfer with the cool gas passing through the conduits, the gaseous heating media exit from the recuperator through an offtake 34. A baffle plate 36 may be extended across part of the upper part of heating chamber 24 (see Fig. 1) for the purpose of forcing the heating gas to follow a zigzag path during its passage through the heating chamber of the recuperator, thereby insuring a thorough circulation of the gas around the outside of conduits 30. However, this baffle plate is not an essential part of the apparatus, for according to the preferred form of the invention the heating chamber is substantially filled around and between the conduits with checker brick or partition walls 38 or with both checker brick and partition walls of refractory or other good heat absorbing, heat radiating and heat resisting material having a relatively low cost per square foot of heating surface as compared with high temperature metal, and the presence of this refractory filling in the heating chamber serves to insure a thorough and uniform distribution of the heating gas and an intimate contacting of the hot gas and the outer surface of conduits 30 throughout each part of chamber 24. The refractory checker brick or partitions 38 are preferably supported on header 26 (see Fig. 1) or on auxiliary supporting girders 40 (see Fig. 8) and when a rectangular housing is employed the heating gases are preferably collected in transverse chambers 42 in the lower portion of the heating chamber, above header 26 and between the metal conduits 30, and from chamber 42 are passed through a horizontal flue 44 to the offtake 34 (see Fig. 8).

The effectiveness of the normal type of recuperator having metal sections or diaphragms 30 is greatly increased by thus placing refractory material 38 around the outer or heating side of the metal walls in the path of the heating gases and spaced at a distance from the wall so that hot gases may circulate around the refractory and between the refractory and the metal wall. The refractory 38 is preferably arranged to present a maximum surface directly facing the outer surface of the conduit for the transmission of heat absorbed from the gas as radiant energy directly from the refractory to the metal. By thus arranging the refractory 38 the current of hot gases entering the recuperator is forced through the narrow paths 46 between two surfaces, one of metal and the other of refractory, each of which takes up sensible heat from the gas by convection. Both the refractory 38 and the metal conduit 30 are designed to present a maximum heat absorbing surface to the heating gas. Heat taken up by the metal surfaces passes rapidly through the metal to the cool gas side, due to the high heat conductivity of the metal and to the temperature differential which exists between the heating gas on one side of the metal and the gas taking up heat on the other. The temperature of the heating gas is at all times higher than that of the refractory in its path for the reason that the refractory is surrounded on all sides by the heating gas, and the temperature of the refractory quickly rises above the temperature of the metal because the metal will always conduct heat away from the heating surface many times faster than heat can be taken up from the gas. As the refractory reaches a higher temperature than the metal surface exposed to the heating gas, heat will be transmitted directly from the surface of the refractory to the metal surface opposite, and as, particularly at high temperatures, the rate of heat transfer by radiation is very high as compared to the rate at which it is transferred by convection, it is possible with the present apparatus to absorb and transmit much more heat from the heating gas to the metal surface of the recuperator conduits per square foot of exposed surface than would be possible if the refractory were not used.

The openings 46 between the metal and the refractory are so restricted that the velocity of the gas passing therethrough is necessarily much higher than it would be if the refractory were not used. This increased velocity of the heating gas has the effect of reducing the thickness of the dead gas films which adhere to the surface of the refractory and to the metal surface of conduits 30 and thereby still further reduces the resistance effect of these gas films to heat transfer. However it is not advisable to reduce the size of openings 46 to such an extent as to make the resistance offered to the flow of heating gas through the recuperator and the resultant pressure drop excessive, and accordingly, to maintain proper spacing between the refractory and the metal and proper alignment between the two surfaces, refractory spacer blocks 52 (see Fig. 9) or bearing knobs 48 built at intervals along the outside of the metal conduits (see Figs. 7 and 8), are employed.

According to the preferred form of the invention metal conduits 30 are equipped with cores 50 of relatively inexpensive material having good heat absorbing and heat resistant properties, such as the ordinary type of refractory firebrick. These cores may be built up of blocks of odd cross section resting on the foundation of the recuperator (see Fig. 1) or they may consist of loose pieces of broken refractory, or thin tiling supported by brackets 52 (see Fig. 9) or by a perforated metal floor at the base of the conduit, as where loose refractory such as that illustrated in Fig. 4 is employed. 5

These refractory cores 50 preferably extend through the whole length of the metal conduits 30 and are centered in the conduit so as to leave an annular passage 54 between the outer surface of the core and the inner metal surface of the conduit for the passage of air, steam or other medium undergoing preheat from distributing chamber 14 to collecting chambers 20 and 20a. Refractory material is readily molded into odd shapes such as 10 those illustrated in Figs. 2, 3, and 4, and by building the refractory cores 50, as well as the refractory checker brick and partitions 38 on the outside of the metal conduits, in shapes of odd cross section so as to expose a large surface to the heating gas and to the air or gas to be heated as compared with the surface of exposed metal, the effectiveness of the metal surface is greatly increased, or in other words it is possible to extract much 15 more heat from the heating gas and to put much more heat into the gas being heated per square foot of metal surface than would be possible if the refractory were not used. 20

Various shapes and arrangements of refractory such as those illustrated in the drawings, particularly in Figs. 2, 3, 4, 5, 6 and 9, may be adopted in accordance with the temperatures and volume of gas undergoing heat interchange. It is of obvious advantage to 25 have the refractory on the outside of the metal diaphragms so arranged that radiant energy will pass directly from the refractory to the metal; and the refractory on the inside so arranged that radiant energy will pass directly from the metal to the refractory. 30 Likewise it is obviously important to have the refractory on the heating side of the metal so arranged that the heating gas will circulate in direct heat transferring relationship 35 with the metal and the refractory; and to have the refractory on the inner or cold gas side of the metal diaphragm so arranged that the gas to be heated will circulate in direct heat transferring relationship with the surfaces of the metal and the refractory. 40

For preheaters in which there is a high pressure drop or turbulent flow of gas to be heated through the metal conduits, the conduits are preferably constructed with a rectangular or other odd shaped cross section 45 such as to provide a relatively large heating surface per unit volume displacement (see Figs. 6 and 9). In employing this type of narrow conduit the refractory cores on the inside and the refractory partition walls 50 around the outside of the conduits may be of light construction, in operations in which the flow of heating gas and the flow of gas to be heated is substantially continuous. For operations in which it is necessary to impart 55 heat continuously to a current of gas or air to be heated, and where it is occasionally necessary to cut off for short intervals the flow of heating gas through the recuperator, refractory partition walls 38 or refractory cores 60 50, or both partition walls and cores of relatively bulky construction, may be used (see Figs. 7 and 8). Thus in cases in which the heat treating or other operation from which the supply of products of combustion or 65 other heating gas is obtained is intermittent, and where it is at the same time desired to continue the preheating of air, steam or other gas, either by passing the gas undergoing preheat through the recuperator conduits as before or by passing the gas through the heating chamber passages of the recuperator in the same direction or in a direction opposite to that normally taken by the products of combustion, it is obviously of advantage to 70 use refractory of relatively large heat storage capacity in the passages surrounding the conduits or inside the conduits or both inside the conduits and in the passages surrounding the conduits. By employing such bulky partition walls and bulky cores it is possible to make use of the known heat storage capacity of the refractory to maintain a continuous supply of heat to the gaseous medium 75 taking up heat during intervals in which the flow of gaseous heating medium is suspended. The size and volume displacement of the partition walls and cores employed is obviously governed by the length of time during which the flow of heating gas is suspended, the volume of refractory employed being chosen according to its heat storage capacity to maintain continuous preheating of the gas taking up heat during the interval in which no heating gas is passed through the recuperator. 80

One advantage obtained by the use of refractory bodies placed in the path of the heating gas and having a large heat radiating surface facing the outside heat absorbing surface of the metal recuperator diaphragm is 85 that with this arrangement it is possible to transmit heat from the heating gas to the metal surface at a greatly increased rate which, while it will usually be well below the maximum heat conducting capacity of the metal, will nevertheless more than double the effective heat absorbing capacity of the metal surface, particularly at high temperatures. The cost of refractory per unit of heating 90 area is generally relatively low as compared 95

100

105

110

115

120

125

130

to the cost of a corresponding area of high temperature metal, and as it is possible by employing refractory to at least double the effective heat absorbing surface of the recuperator and to greatly increase the heat transmitting effectiveness of the recuperator at a relatively small expenditure, largely because of the greatly increased rate at which heat can be transferred by radiation as compared to the rate at which it is transferred by convection, the capacity of the recuperator can be at least doubled without the necessity of increasing the surface of high temperature metal or the size of the recuperator. By using refractory cores, i. e. cores of material capable of absorbing and reflecting radiant heat, positioned in the path of the air or gas taking up heat and preferably having a surface area at least as large as the inner surface area of the metal conduits, it is possible to transmit heat to the gas over substantially double the heating area normally presented by the metal alone, and by absorbing heat radiated from the metal to substantially double the volume of heat normally removed from the inner surface of the metal during a given period, thereby substantially increasing the heating effectiveness of the recuperator per square foot of metal surface. Thus the rate at which heat is transferred from refractory to air is about the same as that at which it is transferred from metal to air, and although the differential temperature will be somewhat less for refractory to air than for metal to air on the inside of the conduits, it is possible and extremely feasible to get more surface on the refractory than on the metal and thereby, with cores such as those illustrated in the drawings, to at least double the heat transfer effectiveness of the recuperator. The rate at which heat is transferred from metal to air by convection is relatively low as compared to the rate at which heat is transferred by conduction through the metal, due partly to the resistance to heat transfer offered by the dead gas films adhering to the metal surface. Consequently there is always a supply of heat radiating from the inner walls of the metal to take the place of the heat transmitted by convection from the surface of the refractory core to the gas or air taking up heat.

The apparatus constituting the present invention is designed primarily to make use of the advantages in heat transfer gained by transmitting heat in the form of radiant energy rather than solely by convection, in securing more effective heat recuperation in operations employing gaseous fuel. However, while designed primarily for such recuperative service the present apparatus can be readily adapted to regenerative in addition to recuperative service by simply employing bulky refractory and making use of the heat

storage capacity of the heat radiating and heat absorbing material.

The term "refractory" whenever used in the specification and claim is intended as a generic term to define heat resistant material capable of absorbing radiant heat and of transmitting heat as radiant energy. 70

The invention having been thus described, what is claimed is:

Apparatus for effecting transfer of heat from a heating gas to a gas to be heated through the medium of heat conducting walls which comprises a housing, heat conducting conduits extending therethrough and each comprising a flat, thin flue, means for passing gas to be heated through said conduits, a flat, thin plate of refractory material inside each flue and having heat absorbing and heating surfaces spaced from and substantially parallel to the inner walls of said flues, means for passing a heating gas through said housing in contact with the outer surfaces of said flues, refractory material in said housing between adjacent flues and outside the same, 85 said outside refractory comprising supporting posts and flat plates, mounted therebetween and spaced from said heat conducting flue walls to form flues for said heating gas, said heat conducting flue walls being provided at spaced points with protuberances 90 engaging said supporting posts to maintain said outer flat plates and heat conducting flues in predetermined spaced relation.

In testimony whereof I affix my signature.
